UNITED STATES PATENT OFFICE.

JAY D. JONES, OF NEW YORK, N. Y.

HEADLIGHT DIMMER.

Application filed April 20, 1922. Serial No. 555,716.

To all whom it may concern:

Be it known that I, JAY D. JONES, a citizen of the United States, and resident of the borough of Manhattan, in the city and 5 State of New York, have invented a new and useful Improvement in Headlight Dimmers, of which the following is a specification.

The object of my invention is to produce 10 a head light dimmer of novel form which may be located within the head light without reconstruction of the head light structure, said dimmer being arranged to effectually eliminate the glare of the head 15 light, said dimmer at the same time being arranged to deflect a maximum amount of light forwardly and downwardly.

A practical embodiment of my invention 20 is represented in the accompanying drawings, in which:—

Fig. 1 represents a vertical longitudinal central section through a head light of usual form, with my improved dimmer located therein.

Fig. 2 represents a front view of the same.

Fig. 3 represents a detail side view of the dimmer.

The head light comprises the usual casing 1, the reflector 2, the high power central 30 lamp 3 and the low power offset lamp 4. The lens 5 is located between the inwardly directed flange 6 of the rim 7 and the outwardly directed stepped flange 8 of the reflector 2, and is secured in position by the brackets 9 and fastening screws 10.

My improved dimmer is located within the head light immediately back of the lens 5, the dimmer illustrated comprising a forwardly flaring ring 11 having a circumferential flange 12 directed outwardly from the front of the said ring and positioned 40 between the lens 5 and reflector flange 8.

The dimmer ring is provided with a plurality of rearwardly and upwardly inclined 45 fixed vanes 13 of considerable depth extending in parallelism across and spaced between the opposite sides of the ring, the lower front edges of the vanes being located substantially in the front plane of the ring and the upper rear edges being located in different vertical planes rearwardly of the back plane of the ring. These vanes 50 overlap in horizontal planes and decrease

in depth from the middle to the top and bottom vanes. The upper rear edges of certain 55 of the vanes are cut away to form spaces 14 into which the lamps 3 and 4 project, thus permitting the vanes to extend a considerable distance into the interior of the reflector shields 16, 17, being provided to prevent the exposure of the lamps through the vanes in a horizontal plane.

A light intercepting plate 15 is provided across the top of the front of the flaring ring 11 to screen the light rays above the 60 top end 12.

By causing the vanes to overlap in a horizontal plane I am enabled to eliminate all glare, the rays being deflected by the vanes downwardly and forwardly. Also by providing vanes of considerable depth I am enabled to use fewer vanes well spread apart, thus allowing the maximum quantity of light to be thrown downwardly and forwardly from the head light.

Furthermore, it will be seen that I have provided a dimmer which is very simple in construction, inexpensive to manufacture and easily positioned within the head light without interfering with the main or auxiliary lamps, the deflector at the same time being very strong and rigid and suitable for use in connection with head lights now in common use, without any redesigning or reconstruction of the said head lights. Furthermore, the deflector is carried by the lamp front, whereby ready access may be obtained for the replacing of lamps, the polishing of the reflector, etc.

It is evident that various changes may be resorted to in the construction, form and arrangement of the several parts without departing from the spirit and scope of my invention, hence I do not wish to limit myself to the particular embodiment herein 90 shown and described, but

What I claim is:—

A dimmer for location within a head light including a forwardly flaring ring carrying a plurality of parallel rearwardly and upwardly inclined overlapping vanes of a considerable depth spaced a considerable distance apart, the lower front edges of the vanes being located substantially in the front plane of the ring and the upper rear 100 edges being located in different vertical 105

planes rearwardly of the back plane of the ring, the upper rear edges of certain of the vanes being cut away to form spaces into which the central and offset lamps projects, shields carried by certain of the vanes for preventing the exposure of the lamps through the dimmer, and a light intercept-

ing plate across the top of the front of the flaring ring to screen the light rays above the top vane of the dimmer.

In testimony, that I claim the foregoing as my invention, I have signed my name this 17th day of April, 1922.

JAY D. JONES.
